UNITED STATES PATENT OFFICE.

THEODORE A. DOUGHTY, OF FARGO, NORTH DAKOTA.

STOVE.

1,402,924.

Specification of Letters Patent. Patented Jan. 10, 1922.

Application filed June 4, 1919. Serial No. 301,612.

To all whom it may concern:

Be it known that I, THEODORE A. DOUGHTY, a citizen of the United States, and a resident of Fargo, in the county of Cass, State of North Dakota, have invented certain new and useful Improvements in Stoves, of which the following is a specification.

My invention relates to stoves and furnaces and covers improved features of construction, arrangement and operation.

Among the important objects of my invention are: to provide improved construction and arrangement which will give a very large radiating surface in a stove of comparatively small size; to provide construction and arrangement which will enable the passage of air in intimate contact with such large radiating surface; to provide construction and arrangement which will produce a long path for the hot gases and sufficient retardation and checking of the flow to give the air flowing through the stove ample time to take on the heat from the flowing gases; to provide construction and arrangement which will cause uniform distribution of the gases throughout their path and to prevent concentration thereof at any point, and also to effect uniform distribution of the air so that the air can most efficiently come into contact with the heat and the greatest heating efficiency result; and in general to provide construction, arrangement and operation in a stove or furnace which will efficiently heat a large volume of air with comparatively small fuel consumption.

The various features of my invention are clearly disclosed on the accompanying drawings in which—

Fig. 1 is a plan view with parts broken away,

Fig. 2 is a rear elevational view with parts broken away,

Fig. 3 is a sectional view on plane 3—3, Fig. 1,

Fig. 4 is a sectional view on plane 4—4, Fig. 1,

Fig. 5 is a sectional view on plane 5—5, Fig. 3, and

Fig. 6 is a sectional view on plane 6—6, Fig. 3.

The stove shown has a rectangular body formed by the front and rear sheet metal walls 10 and 11, the side walls 12 and 13, and the top and bottom walls 14 and 15. A

vertical partition 16 substantially bisects the stove body and extends between the side walls and the top and bottom walls. Between the partition and the front wall 10 the fire box 17 is supported a distance above the bottom 15 to leave the ash pit 18. Above the fire box is the combustion space 19 to which leads the fuel charging chute 20 normally closed by a door 21, the chute being secured to the front wall 10. The fire box is composed of side walls 22 and 23 and front and rear walls 24 and 25 respectively, the walls being preferably formed of plates having spacing ribs 24' extending vertically and having air slots or passageways 25' therethrough. The ribs space the walls from the walls of the stove to leave heat insulating air space, and the slots 25' are open at their lower ends to the ash pit and at their inner sides communicate with the interior of the fire box.

The stove body is supported by hollow front corner posts 26 and 27 and by rear corner posts 28 and 29, the posts at their upper ends being closed while their lower ends terminate in expanded or bell shaped feet or bases 30. Each of the front corner posts has near its upper end an air inlet opening 31 controlled by a slide or damper 32. At their lower ends each post communicates with the ash pit through a passage way 33 as clearly shown in Figs. 3, 4 and 5. The posts shown are cylindrical but only three-quarters round in order that they may receive the respective corners of the stove as clearly shown in Fig. 1. Air to be heated enters through the openings 31 and flows down through the front posts and into the ash pit, and from there through the slots 25' laterally into the fire box. The fire box sides are shown crowned by a rectangular frame 34 forming the blast compartment 35 from which tuyere openings 36 lead into the upper end of the fire box. As best shown in Fig. 5 the top walls of the fire box side plates have the openings 37 through which air may enter from the ash pit and flow through the tuyeres 36. At the bottom of the fire box is the grate 38. Through the slots 25' and the tuyeres 36 adequate air supply is provided for the fuel in the fire box, and if there is an effective chimney suction the air will be forced into the fire box in the form of a blast and intense heat will result.

Between the partition 16 and the rear-wall 11 of the stove body, upper and lower trans-

verse partitions 39 and 40 extend, these partitions at their sides terminating at and being connected by the vertical walls 41 and 42 as clearly shown in Figs. 2 and 6. Extending between the partitions are a number of intermediate vertical walls 43 which subdivide the space between the walls 41 and 42 into vertical passageways 44 and 45. At their lower ends the passageways 45 communicate with the exterior of the stove by vertical openings 46 cut in the rear wall 11 of the stove. At their upper ends the passageways 44 communicate with the openings 47 cut in the partition 16. Inserted in the space above the fire box are the sheet metal elbow structures 48 which register at their inner ends with the respective passageways 47 and which at their upper ends register with the openings 49 in the top wall 14 of the stove. These elbow members together with the passageways 44 form paths diagonally through the stove for air to be heated. The elbow members 48 are spaced apart distances equal substantially to the width of the passageways 45 heretofore referred to. Between the inner ends of the elbow members the partition 16 has the openings 50 therethrough with which the spaces between the elbow members communicate, so that the hot gases and products of combustion rising from the fire box may flow upwardly through the spaces between the elbow members and through the openings 50 into the spaces 45. The lower partition wall 40 has the openings 51 registering with the spaces 45, so that the hot gases and products of combustion may flow downwardly through the passageways 45 into the space 52. This space communicates at its sides with the vertical side passageways 53 and 54 between the stove sides 12 and 13 and the intermediate walls 41 and 42 respectively. The passageways 53 and 54 communicate at their upper ends with the space 55 above the top partition 39, which space communicates with the chimney 56 through the opening 57. The chimney outlet is in the center of the rear section of the stove and the products of combustion and hot gases flowing into the space 52 from the passageways 45 deflect and flow laterally in the space 52 dividing evenly, half going to one side and half to the other, and then upwardly through the passageways 53 and 54, then through the space 55, uniting, and then flowing into the chimney. The spaces between the elbow members 48 and the vertical passageways 45 together with the passageways 53 and 54 cause the gases and products of combustion to be uniformly distributed in their flow through the stove and prevent concentration thereof. The walls forming these various passageways offer a large amount of heating and radiating surface to the air which flows through the passageways 44 and the elbow

members 48 so that air is rapidly and efficiently heated during its circulation through the stove.

As the gases, smoke and other products of combustion approach the stove outlet to the chimney, they will tend to concentrate into compact streams in order to quickly reach the outlet. This, of course, would prevent a considerable amount of heat from being extracted from the gases, and to prevent such concentration and to retard and restrict the flow of the gases I provide the vertical baffle plates 58 and 59 at the ends of the partition 39, these baffle plates terminating short of the top wall 14 of the stove. In the outlet opening 57 to the chimney I insert an annular sheet metal baffle frame 60 which extends downwardly substantially to the level of the upper ends of the baffle plates 58 and 59. The circumference of the annular baffle frame is equal to the combined length of the baffle plates 58 and 59 which extend between the rear wall 11 of the stove and the partition 16. When the gases reach the baffle plates they are retarded and after passing over the tops of the baffle plates they must dip in order to enter the annular baffle frame. The arrangement causes the gases to flow with even distribution through the space 55 and concentration into streams is prevented, maximum heating efficiency being therefore obtained.

I provide a more direct path for the outgoing hot gases and products of combustion when starting a fire, or the fire is low. In the upper partition 39 the escape openings 61 are provided above and in registration with the passageway 45. A slide damper 62 controlled by a stem 63 extending to the exterior of the stove, is provided for opening or closing the passageways 61. When a fire is started the damper is shifted to open the passageways so that the products of combustion can flow directly into the space 55 and to the chimney. After the fire is under way, the damper is shifted to close the passageways and then the gases will have to take the round about circuitous way before-mentioned to reach the chimney.

The rear corner posts 28 and 29 form ventilating structures for the flow of air from near the floor, into the stove. As shown the bases of these posts have each an inlet opening 64 controlled by a slide 65, and at the upper end each post has the passageways 66, these passageways connecting the posts with the passageways 53 and 54 respectively, the foul air from near the floor being then carried upwardly into the stove and out at the chimney.

In order that the chamber 52 may be cleaned of soot or other collected material, a door 67 is provided. A door 68 is also provided through which the ash pit 18 may be cleaned. 69 represents a door giving access

to the combustion chamber 19 below the hopper 20.

My improved stove can be readily constructed of sheet iron or partly sheet iron 5 and casting. Its design is so simple that it can be inexpensively constructed. By virtue of the numerous distributing passageways for the hot gases and the air, and the up and down path sections for the gases, and the 10 various retarding and deflecting means, a large heating surface is presented and a very large volume of air can be quickly heated in the most efficient manner and with minimum fuel consumption. The air inlet openings 15 46 and the air outlet openings 49 communicate with the room in which the stove is placed.

As changes and modifications in the construction, arrangement and operation are 20 possible which could still come within the scope of my invention, I do not desire to be limited to the precise construction, arrangement and operation shown and described, but having described my invention I desire 25 to secure the following claims for Letters Patent.

1. In a stove, the combination of the outer walls, a vertical partition dividing the stove into a front part and a rear part, a fire box 30 in the front part, vertical passageways in the rear part communicating at their upper ends with the front part, side passageways in the stove communicating with the lower ends of said vertical passageways, a chimney 35 communicating with the upper ends of said side passageways, and air passageways extending through said stove between said vertical passageways, said air passageways being open at their lower ends to the exterior 40 of the stove and at their upper ends adapted to charge heated air into the room in which the stove is placed.

2. In a stove, the combination of the stove body, a partition dividing said body into 45 front and rear compartments, a fire pot at the lower part of said front compartment, a chimney outlet at the upper end of the rear compartment, means for admitting air into the front compartment below said fire pot, 50 down draft passageways at the central part of said rear compartment and up draft side passageways in said compartment, said down draft passageways connecting with said front compartment at the upper part thereof 55 and at the lower ends with said up draft passageways and said up draft side passageways communicating with the chimney outlet.

3. In a stove, the combination of the stove 60 body, a partition dividing said body into front and rear compartments, a fire pot at the lower end of said front compartment, means for conducting air to said fire pot from the exterior of the stove, a chimney 65 outlet at the upper end of said rear com-

partment, down draft passageways at the central part of the rear compartment, up draft side passageways in said compartment, said down draft passageways communicating at their upper ends with the front compartment near the top thereof and at the lower ends with said up draft passageways and said up draft side passageways communicating at their upper ends with said chimney outlet, and air passageways alternating 70 with said down draft passageways, said air passageways having their lower inlet ends near the bottom of the stove and their upper outlet ends at the top of the stove. 80

4. In a stove, the combination of the stove body, a fire pot at the lower part of said body, means for conducting air into said fire pot, a chimney outlet at the top of said body, down draft passageways and side up draft 85 passageways in said body, said down draft passageways receiving the products of combustion at their upper ends and communicating at their lower ends with said up draft side passageways, said side passageways 90 communicating at their upper ends with the chimney outlet, and air passageways extending through said body from the bottom to the top thereof, for the upward flow of air to be heated, said air passageways being in 95 intimate contact with said down draft passageways.

5. In a stove, the combination of a stove body, a partition dividing said body into front and rear compartments, a fire pot at 100 the lower end of said front compartment, a horizontal row of openings in said partition near the top thereof, down draft passageways at the central part of said rear compartment connecting at their upper ends 105 with said openings in said partition, up draft passageways at the sides of said rear compartment connecting at their lower ends with the lower ends of said down draft passageways, a chimney outlet at the upper 110 end of said rear compartment, said side passageways at their upper ends communicating with said chimney outlet, a second horizontal row of openings through said partition, air passageways alternating with said down 115 draft passageways and communicating at their upper ends with said openings of the second row and at their lower ends communicating with the stove exterior, and ducts connecting the openings of said second 120 row with the upper end of said front compartment, said ducts being spaced apart for the flow of products of combustion from said front compartment into said down draft passageways. 125

6. In a stove, the combination of a rectangular body, a partition dividing said body into front and rear compartments, a fire pot in the front compartment near the bottom thereof, an ash pit below the fire pot, 130

means for feeding air into said ash pit, air passageways from said ash pit into said fire pot, vertical walls in said rear compartment forming a horizontal row of vertical passageways, said passageways constituting alternately down draft passageways and air passageways, openings in said partition connecting with the upper ends of said down draft passageways for the entrance of products of combustion from said front compartment, said down draft passageways being open at their lower ends, side up draft passageways in said rear compartment communicating at their lower ends with said down draft passageways, a chimney outlet in the upper end of said rear compartment, said up draft passageways communicating with said chimney outlet, said air passageways being open at their lower ends to the exterior of the stove for the entrance of air, other openings in said partition, and ducts extending through the upper part of said front compartment and communicating at their inner ends with said other openings and at their upper ends with the stove exterior.

7. In a stove, the combination of walls forming the stove body, a fire pot at the lower part of said body and a combustion chamber above said fire pot, a transverse partition near the upper end of said body, walls extending downwardly from said partition and forming vertical passageways, said passageways being open at their upper ends to said combustion chamber, side up draft passageways communicating at their lower ends with said down draft passageways and communicating at their upper ends with the space above said partition, an outlet in the top of said stove above said partition adapted for connection with a chimney, said partition wall having openings communicating with said down draft passageways, and a damper for opening or closing said openings, said openings when open permitting direct flow of the products of combustion from said combustion chamber into the space above said partition and to the chimney.

8. In a stove, the combination of outer walls forming the stove body, a partition dividing said body into front and rear compartments, a fire pot in the front compartment near the bottom thereof, the space in said front compartment above said fire pot forming a combustion chamber, a transverse partition wall near the upper part of said rear compartment, walls extending downwardly from said transverse partition forming a row of down draft passageways, there being openings through said vertical partition connecting said combustion chamber with the upper ends of said down draft passageways, up draft passageways at the sides of said rear compartment connecting the lower ends of said down draft passageways.

with the space above said transverse partition, there being an outlet in the top wall of said stove above said transverse partition, and air passageways sandwiched between said down draft passageways, said air passageways being open for the upward flow of air therethrough.

9. In a stove, the combination of the stove body, a fire pot at the lower part of said body, a transverse partition near the top of said body, walls extending downwardly from said partition and forming a plurality of down draft passageways, said passageways at their upper ends communicating with the space above the fire pot to receive the products of combustion, side up draft passageways connecting the lower ends of said down draft passageways with the space above said transverse partition, an outlet to the chimney in the top wall of the stove above said partition, baffle plates extending upwardly from the sides of the partition to be in the path of the flow of gases from the up draft passageways to the space above the partition, and an annular deflecting frame in said outlet extending downwardly toward said partition, said baffle frame cooperating with said baffle plates to spread and distribute the gases in their flow through the space above said partition and toward the outlet.

10. In a stove, the combination of a stove body, a vertical partition dividing said body into front and rear compartments, a fire pot at the lower part of the front compartment, the space above the fire pot forming a combustion chamber, means for supplying fresh air to said fire pot, a transverse partition near the upper end of said rear compartment, walls extending downwardly from said transverse partition to form a horizontal row of down draft passageways terminating a distance short of the bottom of the stove, said passageways at their upper ends communicating with the combustion chamber to receive the products of combustion, up draft passageways at the sides of the rear compartment communicating at their lower ends with the space below the down draft passageways and communicating at their upper ends with the space above said transverse partition, an outlet to the chimney in the top of the stove above said transverse partition, baffle plates extending upwardly from the sides of said transverse partition to be in the path of gases flowing from said up draft passageways into the space above said transverse partition, an annular baffle frame extending through said outlet opening a distance downwardly into the space above said transverse partition, said annular baffle wall co-operating with said baffle plates to deflect and distribute the gases to cause uniform flow thereof through said space above the transverse partition.

11. In a stove, the combination of a rectangular body, a vertical partition dividing said body into front and rear compartments, a fire pot at the lower part of the front compartment, the space above the fire pot forming a combustion chamber, means for feeding fresh air into said fire pot, a transverse partition near the upper part of the rear compartment, walls extending downwardly from said partition to within a short distance of the stove bottom, said walls forming vertical down draft passageways, said passageways communicating at their upper ends with said combustion chamber to receive the products of combustion, up draft passageways at the sides of the rear compartment communicating at their lower ends with the space below said down draft passageways and communicating at their upper ends with the space above said transverse partition, there being an outlet in the top of the stove above the center of the transverse partition, an annular baffle frame extending downwardly from said outlet a distance into said space above said transverse partition, baffle plates extending upwardly from the sides of said transverse partition, said baffle plates being in the path of gases flowing from the up draft passageways into the space above said transverse partition and causing the gases to dip before they can enter the outlet passageway, said annular baffle frame having a circumference equal substantially to the combined length of the baffle plates and co-operating with the baffle plates to spread and uniformly distribute the gases in their flow through the space above said transverse partition.
12. In a stove, the combination of a rectangular body, a fire pot at the lower part of said body, means for feeding fresh air into said fire pot, a transverse partition near the upper end of said body, an outlet in the top of the stove above said transverse partition, baffle plates at the sides of said transverse partition extending upwardly into the space above said partition, an annular baffle wall extending downwardly from said outlet opening, the circumference of said annular baffle wall being substantially equal to the combined length of said baffle plates, said baffle wall and plates co-operating to distribute and spread out the flow of gases through the space above said transverse partition.
13. In a stove, the combination of a stove body formed so as to provide two compartments, a fire box in one of said compartments, a duct extending diagonally upwardly across said compartments through the stove body for the passage of air, said duct being open at both ends and terminating above said fire box, a chimney, a passageway between the second mentioned compartment and the chimney whereby the products of combustion pass upwardly in the first mentioned compartment first into contact with the upper end of said duct, then along said duct into the second mentioned compartment and thence to the chimney.
14. In a stove, the combination of a stove body formed so as to provide two compartments, a fire box in one of said compartments, a plurality of ducts extending through said stove body from the lower portion of the other compartment to the upper portion of the first mentioned compartment open at both ends for the upward passage of air, the upper portions of said ducts being above said fire box, a chimney, means establishing communication between the lower portion of said second mentioned compartment and the chimney, whereby the products of combustion pass upwardly in the first mentioned compartment into contact with the upper ends of said ducts, downwardly in the second mentioned compartment between the ducts and thence to the chimney.
15. In a stove, the combination of a stove body formed so as to provide two compartments, a fire box in one of said compartments, a plurality of ducts extending through said stove body from the lower portion of the other compartment to the upper portion of the first mentioned compartment open at both ends for the upward passage of air, the upper portions of said ducts being above said fire box, a chimney extending from the upper portion of the second mentioned compartment, passageways extending along the outer walls from the lower portion of the second mentioned compartment to said chimney, whereby the products of combustion pass upwardly into the first mentioned compartment into contact with the upper ends of said ducts, downwardly in the second mentioned compartment between the ducts and thence upwardly through said passageways to the chimney.
16. In a stove, the combination of a stove body, a vertical partition dividing said body into two compartments, a fire box in one of said compartments, a plurality of ducts extending diagonally upwardly across said compartments through the stove body for the passage of air, said ducts being open at both ends, the upper ends of said ducts extending across said first mentioned compartment to the outer side wall thereof above the fire box, a chimney, means establishing communication between the lower portion of said second mentioned compartment and the chimney, whereby the products of combustion pass upwardly in the first mentioned compartment into contact with the upper ends of said ducts, downwardly in the second mentioned compartment between the ducts, and thence to the chimney.
17. In a stove, the combination of a stove

body, a fire pot at the lower part of said body, a transverse partition near the top of said body, walls extending downwardly from said partition and forming a plurality of down draft passageways, said passageways at their upper ends communicating with the space above the fire pot to receive the products of combustion, side up draft passageways connecting the lower ends of 10 said down draft passageways with the space above said transverse partition, an outlet to the chimney in the top wall of the stove above said partition, baffle plates extending upwardly from the sides of the partition to 15 be in the path of the flow of gases from the up draft passageways to the space above the partition, and deflecting means cooperating with said baffle plates to spread and distribute the gases in their flow through the 20 space above said partition and toward the outlet.

18. In a stove, the combination of a stove body, a vertical partition dividing said body into front and rear compartments, a fire pot 25 at the lower part of the front compartment, the space above the fire pot forming a combustion chamber, means for supplying fresh air to said fire pot, a transverse partition near the upper end of said rear compartment, walls extending downwardly from 30 said transverse partition to form a horizontal row of down draft passageways terminating a distance short of the bottom of the stove, said passageways at their upper ends communicating with the combustion chamber 35 to receive the products of combustion, updraft passageways at the sides of the rear compartment communicating at their lower ends with the space below the down draft passageways and communicating at 40 their upper ends with the space above said transverse partition, an outlet to the chimney in the top of the stove above said transverse partition, baffle plates extending upwardly from the sides of said transverse 45 partition to be in the path of gases flowing from said up draft passageways into the space above said transverse partition, a deflector in the space above said transverse partition, said deflector cooperating with 50 said baffle plates to deflect and distribute the gases to cause uniform flow thereof through said space above the transverse partition.

In witness whereof, I hereunto subscribe 55 my name this 31st day of May, A. D., 1919.

THEODORE A. DOUGHTY.
